UNITED STATES PATENT OFFICE.

THOMAS BAUER, OF LA FAYETTE, INDIANA.

PAPER-MAKING MACHINERY.

1,071,021.

Specification of Letters Patent. Patented Aug. 26, 1913.

Application filed November 25, 1910. Serial No. 594,019.

To all whom it may concern:

Be it known that I, THOMAS BAUER, a citizen of the United States, residing at La Fayette, county of Tippecanoe, State of Indiana, have made a certain new and useful Invention in Paper-Making Machinery, of which the following is a specification.

This invention relates to improvements in paper making machinery and particularly to the suction box employed in connection with machinery of this class.

The object of the invention is to provide means for relieving the traveling belt or carrier for the pulp of undue and unnecessary wear and friction while subjected to the action of the suction.

Other objects of the invention will appear more fully hereinafter.

The invention consists substantially in the construction, combination, location and relative arrangement of parts, all as will be more fully hereinafter set forth, as shown in the accompanying drawings, and finally pointed out in the appended claim.

Referring to the accompanying drawing and to the various views and reference signs appearing thereon, Figure 1 is a broken view in top plan of a suction box embodying the principles of my invention, the pulp carrying belt being removed. Fig. 2 is a view in vertical cross section of the same on the line 2, 2, Fig. 1, looking in the direction of the arrows, the pulp carrier being shown in operative relation with respect to the suction box. Fig. 3 is a broken view in vertical longitudinal section on the line 3, 3, Fig. 1, looking in the direction of the arrows. Fig. 4 is a broken, detached, detail view in longitudinal section of one end of the suction drum or roll. Fig. 5 is a detached detail view, in front elevation, of the journal support for one end of the suction roll or drum. Fig. 6 is a sectional view of the same on the line 6, 6, Fig. 5, looking in the direction of the arrows. Fig. 7 is a broken view in section, similar to Fig. 2, showing a modified form of pulp carrying belt embodying the principles of my invention.

In the operation of making paper pulp, the wet pulp is usually applied to a felt or other form of porous belt or endless carrier and while the carrier is moved along it is passed over a suction box constructed to permit the water in the pulp to be drawn therefrom by suction action. The suction action to which the carrier is subjected imposes

great friction on the carrier causing the same to work hard, and to wear out rapidly.

It is among the special purposes of my present invention to provide a suction box structure which relieves the pulp carrier of excessive friction and wear while passing thereover.

In carrying out my invention I propose to employ a perforated suction drum or roll, and journal the same within the suction box so as to be capable of free rotation, the periphery of said roll extending slightly through the opening in the suction box and into position to receive the bearing contact of the traveling pulp carrier as it passes thereover whereby the carrier, while being subjected to the suction action applied through the perforations in the roll or drum is passing over the rolling surface of the drum or roll, that is the roll or drum revolves as the carrier is drawn thereover, thereby greatly relieving the carrier of excessive friction and wear. I also propose, in some instances to employ a traveling carrier having a wire gauze or similar fabric applied to the under or wearing surface thereof, or incorporated therein, and which, contacting with the surface of the suction box or roll or drum takes the wear and friction from the felt or other porous pulp carrier.

In the drawings 10, designates the suction box. This is a chamber which is closed except for a longitudinal opening 11, in its upper surface, and an opening 12 for suitable connection with an exhaust pump. The area of the opening 11 in the upper surface of the suction box may be limited and restricted by the wearing plate 13, applied to the flat surfaces of the bounding edges of the longitudinal opening 11 in the suction box, said wearing plate having a longitudinal opening 14 therethrough of suitably restricted area and through which the suction action is applied to the carrier. The wearing plate 13, presents a flat outer surface over which the pulp carrier operates. In this manner only that portion of the carrier which registers with the opening 14 in the wearing plate, and through said opening, and opening 11, in the suction box with the interior of said box, is subjected to the suction action. A hollow roll or drum 15, is suitably journaled within the suction box, and in such relation as that its peripheral surface protrudes slightly through the open-

ing 14, in wearing plate 13, so as to take the bearing contact of the pulp carrier when passing thereover. The shell of the drum or roll 15 is perforated as indicated at 16. It will be understood that the suction box is closed except for the openings for the exhaust pump connection and that through which the perforated periphery of the roll or drum 15 protrudes. Consequently as the pulp carrier is progressed over the exposed surface of the perforated drum or roll 15, it is subjected to the suction action of the exhaust pump. This action would impose an excessive friction upon the carrier by drawing the same down tight against the exposed surface of the drum or roll 15, thereby subjecting the same to undue wear and strain. To obviate this, at least to a very large extent, I mount the roll or drum 15, to freely rotate so that it revolves as the carrier is drawn along thereover, and hence, instead of the carrier being drawn over a fixed surface while under the suction action, it moves over a moving surface, that is, the surface of the roll or drum with which it contacts rolls or moves along with the carrier. The carrier is indicated at 17, and, as above indicated, it is of felt or other convenient porous material.

30 A convenient arrangement of mounting for the perforated suction roll or drum, to permit of the free rotation thereof, within the suction box, is shown wherein each open end of the shell of the drum receives a spider supporting frame 18, carrying a short stub shaft 19, having one end thereof extending into a journal bearing 20, therefor, said bearing being carried in a support 21, mounted in the suction box. Means are provided for adjusting the journal supports 21, so that the extent to which the roll or drum 15, protrudes through the openings 11, 14, may be regulated. An adjusting set screw 22, is shown for this purpose, the journal

support 21 being mounted for adjusting 45 movement in a guide way 23, in the suction box. If desired, and in order to still further insure against excessive friction and wear, I may apply a wire gauze or netting 23, to the pulp carrier, as indicated in Fig. 7, this wire netting or gauze taking the wear which would otherwise be imposed on the pulp carrier. The bearing 20, may if desired be a roller bearing.

Having now set forth the object and nature of my invention, and a construction embodying the principles thereof, what I claim as new and useful and of my own invention, and desire to secure by Letters Patent is,—

55 In a paper making machine, a suction box having a longitudinal opening therein, a perforated roll or drum arranged inside said box for the peripheral surface to protrude through the longitudinal opening in said box, the bounding edges of the opening in said box being flat to form a bearing surface, an imperforate rectangular plate having a central longitudinal opening therethrough and adapted to be applied to said bearing 65 surface, the central longitudinal opening in said plate serving to limit the suction area of the opening in the box, whereby all the suction action takes place through the perforations in the roll, said roll or drum being 70 journaled to freely rotate, a pulp carrier operating over the exposed surface of the roll or drum, and a wire gauze or netting applied to the carrier to take the wear 75 thereof.

80 In testimony whereof I have hereunto set my hand in the presence of the subscribing witnesses, on this 26th day of October A. D., 1910.

THOS. BAUER.
